(57) **CLAIM**

The ornamental design for a display screen or portion thereof with graphical user interface, as shown and described.

DESCRIPTION

The FIGURE is a front view of the claimed design for a display screen or portion thereof with graphical user interface.

The broken lines showing portions of a display screen, text, and other features of the display screen or portion thereof with graphical user interface depict environmental structure and form no part of the claimed design. The dash-dot lines indicate a boundary or perimeter of the graphical user interface image and form no part of the claimed design. In the FIGURE, the perimeters of the portion of the underlying displaying screen and the graphical user interface are understood to be flush.
